MICROPHONE

Louis R. Burroughs, Buchanan, Mich., assignor to Electro-Voice, Incorporated, Buchanan, Mich.

Application March 3, 1955, Serial No. 34,865

Term of patent 14 years

(Cl. D26—14)

I claim:

The ornamental design for a microphone, substantially as shown.
